HARRY E. LYNN, OF MAYWOOD, AND FRED LAMBERT, JR., OF EAGLE ROCK, CALIFORNIA, ASSIGNORS OF TWENTY-SEVEN PER CENT TO WILLIAM A. SMITH, EIGHTEEN AND ONE-FOURTH PER CENT TO WILLIAM A. VOCK, AND EIGHTEEN AND ONE-FOURTH PER CENT TO FOX M. BOSWELL, ALL OF LONG BEACH, CALIFORNIA

BUSHING FOR ROTARY TABLES

Application filed May 14, 1929, Serial No. 362,990. Renewed December 13, 1932.

This invention has to do with a bushing for a rotary table and it is a general object of the invention to provide an improved, practical, and economical bushing for use in the table of a rotary well drilling outfit.

In the drilling of wells with the rotary method it is common to use what is known as a rotary unit, or table, to drive the drill string. In standard equipment a Kelly or 10 drill stem is attached to the drill string and is engaged by bushings carried in the rotary table, the engagement being such as to allow the drill stem to be raised and lowered through the table while the driving engagement is maintained between the table and drill stem. In practice considerable friction and wear occurs between the drill stem and the bushings carried in the rotary table.

The present invention provides an improved form of bushing construction for use in a rotary table, and the invention has among its objects the provision of a bushing which materially reduces wear and friction, which operates effectively and smoothly, and which 25 is economical and commercially practical.

It is a general object of the present invention to provide a bushing that will pass a drill stem with a minimum of friction and at the same time maintain an effective driving 30 engagement with the drill stem.

It is another object of the invention to provide a construction whereby drill stems of various sizes can be accommodated conveniently and at low costs.

35 It is a further object of the present invention to provide a device of the character mentioned which is sturdy and durable. The device provided by the invention is such as to effectively withstand the severe use that 40 frequently comes upon the bushings of a rotary table, and it is of such nature as to operate with little wear or deterioration.

Another object of the invention is to provide a device of the character described that 45 is safe to operate. The invention provides a construction and arrangement which minimizes the danger of parts being broken or lost in a manner to fall into the well bore or otherwise cause trouble.

50 It is another object of the present invention

to provide a construction for a device of the character mentioned which embodies a plurality of rotatable members to engage the drill stem but is free of delicate locking devices or retaining means subject to failure 55 or such as to cause trouble or delay in operation.

The various objects and features of the invention will be best and more fully understood from the following detailed description 60 of a typical form and application of the invention, throughout which description reference is had to the accompanying drawings, in which:

Fig. 1 is a detail sectional view illustrating 65 a typical rotary unit with a Kelly or drill stem arranged through it and with a bushing device provided by this invention forming a driving connection between the unit and drill stem. Fig. 2 is a plan view of the parts shown in Fig. 1. Fig. 3 is an enlarged side view of the construction provided by this invention showing certain parts broken away to be in section. Fig. 4 is a plan view of the device shown in Fig. 3 with parts broken away to 70 show in section. Fig. 5 is a top or plan view of one of the cages of the construction provided by this invention. Fig. 6 is a vertical sectional view of a cage, being a view taken as indicated by line 6—6 on Fig. 5, and Fig. 75 7 is a side view of a cage, being a view taken as indicated by line 7—7 on Fig. 6.

The device provided by this invention is intended primarily for use in connection with this standard or common form of rotary drilling equipment, it being understood, however, that various modifications and variations may be made in the invention to accommodate it to various types of equipment. To facilitate an understanding of the invention, we have illustrated it as applied to a standard form of rotary unit 10 and drill stem 11. The rotary unit 10 has in addition to the various parts common to devices of this character, a table 12 with a central vertical opening 13 carrying a master bushing 14. The master bushing is held in the table against rotation and has a central vertical opening passing the drill stem 11 and adapted to receive a bushing for establishing a driving connection between the 100

master bushing 14 and the drill stem 11. The opening in the master bushing has a tapered or downwardly convergent portion 15 which is round in cross section and has a straight 5 polygonal portion 16 immediately above the tapered portion 15. In practice the polygonal portion of the bushing opening is substantially square in cross section.

The device provided by our invention is 10 adapted to be carried in the master bushing 14 and is designed to engage the drill stem 11 to establish a driving connection between the master bushing 14 or table 12 and the drill stem 11. The device includes, generally, a 15 body 17 to be mounted in the rotary unit 10, a plurality of cages 18 to be carried in the body 17, means 19 for retaining the cages in the body, and rollers 20 carried in the cages to engage the drill stem 11. When 20 the device is to be used in connection with standard equipment, such as we have referred to and such as is illustrated in Figs. 1 and 2 of the drawings, the body 17 is designed to fit the opening of the master bushing 14. The 25 body 17 is provided with a tapered lower portion 21 to fit the tapered opening 15 of the master bushing and is provided with a polygonal portion 22 immediately above the portion 21 to fit the portion 16 of the opening 30 of the master bushing 14. In the particular design of the invention illustrated, the body 17 extends or projects a substantial distance above the portion 22, giving the device considerable length and making it possible to obtain 35 roller carrying cages of substantial length.

The body 17 has a central vertical opening extending through it, said opening being designed and proportioned to accommodate the 40 cages 18. In the form of the invention illustrated the cages 18 are adapted to be arranged in the body 17 through its upper end and the cage receiving portion of the body opening is shaped to effectively support the 45 cages in operating position. In the case of a device designed to accommodate a standard form of drill stem, such drill stem being substantially square in cross section, the device is provided with four cages 18, and the cage 50 receiving portion of the body opening is formed with four walls 23 which support the cages.

A rest or stop 24 is provided in the body 17 near its lower end to limit downward movement of the cages in the body. The stop 24 55 may be in the form of a flange projecting inwardly in the body opening to extend under the cages, as clearly shown in Fig. 3. In practice considerable strain may at times 60 come upon the stop 24, and therefore it is desirable to reinforce it by means of braces or ribs 25.

The cages 18, which are arranged in the body 17 and which carry the rollers 20, are adapted to be arranged in the body 17

through its upper end, and when in place are supported by the walls 23 of the body and stop 24.

Each cage 18 is preferably in the form of a rectangular frame adapted to fit against one of the side walls 23 of the body opening. The frame formation of the cage may include spaced vertical sides 30, a top 31 joining the upper ends of the sides, and a bottom 32 joining the lower ends of the sides. 70 In accordance with the preferred form of the invention, the cages are designed to mesh or cooperate so that they hold each other in place, that is, in operating position in engagement with the walls 23 of the body opening. In the form of the invention shown, one side 30 of each frame is provided with a vertical recess 33 in one corner to receive the corner of the adjoining frame. The manner in which the frames are recessed and fit 75 together is clearly illustrated in Fig. 4 of the drawings. With this arrangement the frames hold one another against falling inwardly.

The rollers 20 are mounted horizontally in 80 the cages 18 so that they project inwardly from the cages in a manner to engage the drill stem 11. The several rollers carried by each cage 18 are located in vertical alignment, that is, one above the other, in the 85 manner clearly illustrated in Figs. 3, 6 and 7 of the drawings.

The rollers 20 are sufficiently long and are 90 so located in the cages 18 as to have effective bearing or driving engagement with the drill stem 11. In this connection it may be noted that the cages 18 and rollers 20 may be designed so that the rollers engage the drill stem 11 in a manner such as is illustrated in 95 Fig. 4 of the drawings.

In accordance with the preferred form of the invention, the rollers are mounted in the cages 18 by means of pins 40 which project through the rollers and have end portions 100 projecting into openings 41 provided in the 105 sides 31 of the cages 18. In practice the rollers 20 are made of such length as to extend substantially the entire distance between the sides 30 of the cages and are spaced apart vertically so that there is working clearance 110 between adjoining rollers. The pins 40, which mount the rollers 20, preferably fit tightly in the rollers and have their projecting end portions rotatably mounted in the 115 openings 41 in the cage 18. By this construction the cage, rollers, and pins, when assembled, form a unit which is free of locking devices or other parts subject to failure or requiring attention.

In assembling the construction the rollers are placed between the sides of the cage and the pins forced or pressed through the rollers until their end portions are in proper position in the openings 41. For the purpose of lubrication vertical openings 45 may be

formed in the sides 30 of the cages 18 in a manner to communicate with the pin support openings 41, as clearly shown in Figs. 6 and 7 of the drawings. Suitable lubricant 5 may be supplied to the openings 45 through fittings 46 applied to the ends of the openings as shown in Fig. 6. With this arrangement, an occasional application of a suitable lubricant keeps the unit in perfect working 10 condition.

The locking or retaining means 19, provided for holding the cages 18 in the body 17, is in the nature of a clamp device applied to the upper end portion of the body 17 to engage 15 and hold the cages 18. In the preferred form of the invention the locking means includes a ring 50 screw threaded to the upper end portion of the body 17 and having a flange portion 51 overhanging or 20 projecting inwardly over the upper ends of the cages. This is a simple, effective construction for retaining the cages in the body. It is to be noted that this construction permits 25 of the cages being removed from the body quickly and without the aid of special tools or equipment. The clamping device or ring is preferably provided with a lock or setting means to prevent it from working loose. In the construction illustrated we 30 provide a screw threaded opening 81 in the flange 51 and arrange a locking pin 80 in the opening 81 to project into a socket in the upper end of the body. This construction is clearly illustrated in Fig. 3 of the drawings.

35 In using the construction provided by this invention, it is applied to the rotary unit in the manner illustrated in Figs. 1 and 2 of the drawings and during operation of the equipment the table is rotated so that driving strain is communicated through the device to the drill stem 11. The numerous rollers carried in the cages provide ample bearing 40 on the drill stem so that the rotational strain is properly communicated between the unit 10 and drill stem 11. The rollers 20, being mounted on horizontal axes, allow free movement of the drill stem vertically through the unit at all times, that is, when the table is being rotated or when it is standing still. 45 The free operation of the drill stem through the device operates to materially improve the action of the drilling equipment as it prevents binding and causes the equipment to operate smoothly. When it is desired to 50 use a drill stem 11 of a different size, it is unnecessary to replace the entire device provided by this invention by one of a different size. With the present invention it is merely necessary to release the retaining means 19 55 by releasing the pin 80 and disengaging the ring 50 from the body 17, remove the cages 18, and replace them with cages of different proportions, that is, with cages proportioned to fit the drill stem 11 to be used. Thus it 60 will be apparent that the present invention 65

provides a construction whereby a single device, equipped with sets of cages of different sizes, may accommodate drill stems of different sizes. This feature of the invention is very important as it makes it unnecessary for an 70 operator to purchase complete units or devices for each size drill pipe that he may desire to operate; further, the removable cage construction that we have provided makes it possible to easily, quickly, and economically 75 replace the wearing parts, that is, those parts subject to wear or injury.

Having described only a typical, preferred form of the invention, we do not wish to limit ourselves to the specific details set forth, 80 but wish to reserve to ourselves any changes or variations that may appear to those skilled in the art or fall within the scope of the following claims.

Having described our invention, we claim: 85

1. In combination, a rotary table, a master bushing carried by the rotary table and having an opening, a drive bushing body carried in said opening and having a vertical opening extending through it adapted to 90 pass a drill stem, a plurality of cages in the body, means for removably retaining the cages in the body, and rollers carried in the cages for engaging a drill stem, the said means including a member screw threaded on the body and extending over the body opening to engage the cages, and a screw for locking the member in position. 95

2. In combination, a rotary table, a master bushing carried by the rotary table and having an opening, a drive bushing body carried in said opening and having a vertical opening extending through it adapted to pass a drill stem, a plurality of cages in the body, means for removably retaining the cages in 100 the body, and rollers carried in the cages for engaging a drill stem, the said means including a member screw threaded to the body. 105

3. In combination, a rotary table, a master bushing carried by the rotary table and having an opening, a drive bushing body carried in said opening and having a vertical opening extending through it adapted to 110 pass a drill stem, a plurality of cages in the body, means for removably retaining the cages in the body, and rollers carried in the cages for engaging a drill stem, the said means including a member screw threaded to the body, and means for locking said member 115 in operating position. 120

4. In combination, a rotary table, a master bushing carried in the table, a body carried in an opening in the master bushing and having an opening for passing a drill stem, and a plurality of roller carrying cages arranged in the body opening, each cage having a recess to receive a portion of an adjoining cage so that the cages are held in position to pass a polygonal drill stem, and means for retain- 125 130

ing the cages in the body, said means including a ring screw threaded on the upper end of the body, and a flange on the ring extending over the body opening to engage the cages.

5. In combination, a rotary table, a master bushing carried in the table, a body carried in an opening in the master bushing and having an opening for passing a drill stem,
10 a plurality of cages arranged in the opening in the body, rollers carried by the cages to engage a drill stem, and means for retaining the cages in the body including a ring screw threaded to the body.

15 In witness that we claim the foregoing we have hereunto subscribed our names this 6th day of May, 1929.

HARRY E. LYNN.
